FLUSHING VALVE

Thomas F. Payne, Cincinnati, Ohio

Application August 15, 1931, Serial No. 557,230

6 Claims. (Cl. 137—93)

This invention is for a flushing valve for use on water closets and relates to that type of valve which is coupled directly to the water supply line without requiring the use of the reservoir or 5 tank.

The invention is particularly applicable for use in connection with water closets having a rim discharge and a jet discharge and when used with a bowl of this type it is constructed to deliver water first to the rim, then to the jet, and then to the rim. In this respect it constitutes an improvement on the invention covered in my prior United States Patent No. 1,660,352, dated February 28, 1928.

15 In valves of this type there is usually a movable element attached to an operating head which is operated in the opening direction by a push rod, as disclosed in my said patent, or other manual effort, or by fluid pressure, while a spring 20 or weight is generally relied upon to assist in operating the valve in the reverse direction, to a closed position. According to the present invention, the valve is normally held closed by fluid pressure. The release of the fluid pressure on 25 one side of the operating head causes the valve first to be opened by the pressure of the incoming water and then to be closed by the water pressure from the same source after the release valve has closed. It thereby eliminates any requirements for springs or push rods.

It is a known fact that when a valve is located on the end of a valve line, and the valve has a waterway through it as large or nearly as large as the water line, that as soon as the valve is 35 opened, the water pressure near the end of the line is practically all lost, and when water operated flushing valves are placed on the ends of water lines having low pressure, when the valve is operated there is not enough water pressure in 40 the valve to open it fully, and often when the valve is opened full, there is not enough water pressure to close it. Due to the alternating function of this invention the movable element necessarily must have a long travel both in its 45 opening and closing movements. The waterways through this invention are not as large as the waterways of the source of supply, thus at all times, no matter how long a travel the movable element may have, the waterways of this invention are always of a smaller area than the source of supply, or at least so proportioned with 50 respect thereto so as to insure conserving enough water pressure on the movable element to fully open and close the valve on reasonably low water pressure. It thereby eliminates any requirement for push rods, springs, or weights to assist in the operation of the movable elements.

A further object of my invention is to provide means, when a vacuum occurs in the source of 55 water supply and the water closet is full of

water, that will prevent the said vacuum from opening the valve and drawing the water from the closet through the valve and into the water supply pipe.

Another object of this invention is to provide 5 a movable element that is composed of all the moving parts (except the pressure release valve) of the valve combined into one unit, so that the said unit may be easily removed from the valve body if it becomes necessary to repair or replace 10 any of its parts.

The invention further contemplates a novel type of mounting for connecting the valve to the bowl by means of which the connection may be easily and securely made and the distribution 15 of the water to the jet and the rim provided for.

The invention may be readily understood by reference to the accompanying drawings, in which

Figure 1 represents a longitudinal vertical section through a valve assembly constructed in 20 accordance with my invention, the valve being shown in the normal closed position;

Figure 2 is a view of the movable parts showing the distributing valve in the position which it initially assumes in the first part of its move- 25 ment to open position;

Figure 3 shows the position of the parts with the valve fully opened;

Figure 4 is a view similar to Figure 2 showing the parts just before the removal thereof to the 30 normal closed position;

Figure 5 is a detail sectional view on a larger scale showing the connection of the valve to the bowl;

Figure 6 is a detail section through one of the 35 connector members;

Figure 7 is a transverse section in the plane of line VII—VII of Figure 6;

Figure 8 is a fragmentary sectional view in the plane of line VIII—VIII of Figure 6; 40

Figure 9 is a side elevation, partly broken away, showing a modification of the arrangement of Figure 1 wherein a diaphragm is used in place of a plunger;

Figure 10 is a view similar to Figure 9 of a 45 modification of the valve when it is constructed for use with a closet bowl in which no special provision is made for alternating a discharge between the rim and jet;

Figure 11 is a detail view of the plug and wiper 50 assembly on the operating head; and

Figure 12 is a perspective view of the wiper element itself.

Referring to the valve construction as shown in Figure 1, 2 designates a valve body having a 55 water inlet connection 3, this connection being threaded for connection with a standard pipe thread. In the upper part of the valve body 2 is a pressure chamber 4, this chamber being closed by a removable cap 5 which screws into the top 60

of the valve body, a gasket being interposed between the two to provide a tight seal. Below the pressure chamber 4 is a cylinder or sleeve portion 6 in which is the vertically reciprocable valve member 7. The valve member 7 comprises a hollow cylindrical body having a central vertical partition 8 dividing the inside of the valve into two chambers 9 and 10. In the upper wall of the chamber 9 is a substantially semi-circular slot 11 and near the lower end of the chamber 9 is a substantially semi-circular slot 12, the slot 12 being much wider than the slot 11, or otherwise having a larger area than the slot 11 so that water entering the slot 11 may, when the parts 15 are in the proper position, flow out of the slot 12 without building up any back pressure in the chamber 9.

The valve body 7 is also provided with an inlet passage 13 in the form of a slot through which 20 water may enter the chamber 10. The chamber 10 is open at its lower end, as indicated at 14, to provide a discharge, and the area of the discharge 14 is considerably larger than the area of the slot 13 in order that no back pressure will be built 25 up when water is discharging through the slot 13.

On top of the cylindrical valve body 7 is an operating head 15. The head 15 carries a washer 16 which closes the upper end of the valve body 7 and which is adapted to seat on the annular seat 17 30 at the top of the cylindrical valve chamber 6.

Passing through the operating head 15 is a transverse passage 18 communicating with a vertical passage 19 in which is a ball check valve 20, the ball serving to permit the flow of fluid from 35 the passage 18 upwardly, but serving to prevent the flow of fluid in the reverse direction. Carried on the operating head 15 is a removable dome 21. In Figure 1 I have shown this dome as having a flange 22 for holding a cup leather 23 in 40 place, this cup leather bearing against the inner walls of the cylindrical pressure chamber 4. The dome 21 carries a removable plug 24 having a central passage 25 therein. In the central passage 25 is a non-circular pin 26 and on the lower end 45 of the pin 26 is an integral disc or flange 27 adapted to rest on the notched flange 28 at the bottom of the plug 24. A compression spring 29 within the dome serves to urge the pin 26 upwardly, holding the flange 27 against the notched 50 flange 28.

By reason of the fact that the flange 27 seats on a notched flange 28, which arrangement is more clearly shown in Figures 11 and 12, communication may always be established from the 55 passage 18 through the passage 19 around the ball 20 into the dome 21 under the flange 27 and up around the non-circular pin 26 into the pressure chamber.

In the upper part of the pressure chamber 4 60 is a fluid outlet port 30 communicating with a by-pass 31, this by-pass being formed in a lateral extension 32 on the body of the valve casing. This lateral extension supports a control valve mechanism of a familiar and well-known type. This 65 control valve includes a seat 33 against which a reciprocable valve member 34 is normally seated. The valve member 34 is carried on an operating rod 35 passing through a packing gland and normally urged to the closed position by means of a compression spring 36 acting against a disc 37 carried on the outer end of the rod 35. At 70 38 is a universally tiltable lever having a portion 39 adapted to contact with the disc 37. When the 75 handle 38 is moved in any direction the rod 35

is pushed inwardly to unseat the valve 34 from its seat 33. The port which is closed by the valve 34 leads into a by-pass 40 and 41.

At the lower end of the valve cylinder 6 is a threaded extension 42 into which is screwed an inner discharge pipe 43. On the lower end of the valve body is a similar threaded extension 44 into which is screwed a second pipe 45, the second pipe 45 being concentric about the pipe 43.

In the valve body is an annular passageway 10 or channel 46 and this communicates through vertical passages 47 with the lower end of the valve body so that water flowing into the annular channel 46 may discharge into the outer pipe 45. The port 12 and passage 46, while larger than 15 port 11, are relatively narrow so that the valve moves rather quickly in moving the ports 12 and 46 out of register, thus assuring a full vertical movement of the valve. The by-pass 41 from the control valve opens into one of the vertical passages 47.

On the inside of the top of the cap 5 is a threaded socket 50 into which is screwed a plug 51 having a vertical extension 52 thereon, the top of this extension having a slot 53 by means of 25 which a screw driver may be engaged therein. By turning the stem 52, the plug 51 may be screwed up and down in the socket 50. The extension 52 is sealed by a gland 54. The head of the screw 53 in the gland is covered by a removable cap 55. 30

Leading from the water connection 3 is a port or passage 56 communicating with an annular chamber 57 under the operating head below the cup 23.

The operation of the valve may now be described. It may be assumed that the chamber 4 is filled with water which cannot escape through the by-passes 30, 31, 40 and 41 because the valve 34 is closed. The connector 3 is of course connected with a source of water pressure, such as the ordinary house or building supply line, and this pressure communicates through the port 56 and the annular chamber 57 with the underside of the plunger or operating head. There is of course no water pressure in either of the chambers 9 and 10. Consequently the area of the operating head subjected to the downward pressure of fluid in the pressure chamber 4 is greater than the area of the operating head subjected to upward pressure because there is no upward pressure on that part of the underside of the piston which is covered by the cylindrical valve 7. The water pressure being over the larger area of the top of the operating head keeps the valve closed. When it is closed the washer 16 is tightly seated 55 on the annular seat 17 and no water can pass this seat.

When the handle 38 is moved in any direction to open valve 34, the pressure in the chamber 4 is released, the water draining from the chamber 4 through the port 30, the passage 31, and through the valve 34, the passages 40, 41 and 47 into the pipe 45. When the water pressure exerted on the operating head in the chamber 4 is released, the water pressure in the annular chamber 57 forces the operating head upwardly. This upward movement quickly raises the slot 11 above seat 17 and some of the incoming water will then flow through the slot 11 into the valve chamber 9 and out of the slot 12. At this time 70 the slot 12 will be in register with the annular channel 46, and water flowing out of the slot 12 will be discharged into the pipe 45 which leads to the jet of the closet bowl. The slot 11 and the slot 13 each have an area which is less than the 75

area of the port 56 through which the incoming water from the connector 3 enters the valve. By reason of this fact the water will not flow through the passage 11 as fast as it can be supplied, the differential pressure resulting from the fact that the water cannot escape as fast as it is supplied, causes the operating head to continue to move up until the port 12 has moved out of register with the annular groove 46. The upward travel of the operating head is continued further until the slot 13 is above the annular seat 17 and reaches the position illustrated in Figure 3, at which time water will flow through the slot 13 down the chamber 10 and be discharged into the inner pipe 43, from whence it flows to the rim of the bowl.

The travel of the operating head and the cylindrical valve member 7 from their position shown in Figure 1 to their position shown in Figure 3 must necessarily be fast. This is necessary for the reason that if the slot 12 does not rapidly pass the annular channel 46, some of the water pressure exerted on the under side of the operating head will be lost, so that the valve will not open fully to the extent that the slot 13 will rise above the annular seat 17. To prevent the aforesaid loss of pressure, it is necessary that the slots 11 and 13 be of sufficiently smaller area than the source of supply to conserve enough pressure to operate the valve and still be of sufficient area to pass enough water to flush this type of water closet.

When the operating head and the reciprocable valve member 7 are in the position illustrated in Figure 3, the slot 12 is out of register with the annular chamber 46 and the slot 11 is in register with the annular chamber 57, as is also the slot 13.

After the operating head and cylindrical valve member 7 have reached the position shown in Figure 3, the operator will have released the handle, and the spring 36 will cause the valve 34 to close, thus stopping the escape of water from the pressure chamber 4. Some of the water will then flow through the passage 18, up the passage 19, past the ball check 20, under the flange 27 on the pin 26 and around the pin 26 into the pressure chamber 4. Since the water cannot escape from chamber 4, pressure will build up in this chamber. This water pressure will be exerted on the top of the operating head, and as the top side of the operating head is of greater area than its underside, a greater pressure will be exerted on the top side, which will force the operating head downward until the washer 16 is seated on the annular seat 17.

When the operating head and the cylindrical valve member start on their downward travel, the slots 11 and 13 are in register with the annular chamber 57. The water passes through both slots 11 and 13, and enters the chambers 9 and 10, and as the slots 12 and 12a are out of register with the annular channel 46 and the enlarged part of the sleeve portion 6, the water flows through slot 13, through chamber 10 into the pipe 43 which conducts it to the rim of the closet. As the operating head and the cylindrical valve member continue their downward travel, the slot 13 is covered by the top end of sleeve 6 at the annular seat 17, thus stopping the flow of water through the slot 13. At this time the slot 12 comes into register with the annular chamber 46, as shown in Figure 2. The water then is forced through slot 11 into the chamber 9 and out through the slot 12 into the

annular channel 46, then through the passage 47 into the pipe 45, which conducts it to the jet passage of the closet bowl.

As the operating head further continues its downward travel, the slot 12 moves out of register with the channel 46, the water stops flowing through slot 12, and the slot 12a moves into register with the enlarged portion of the sleeve 6 as shown in Figure 4. When the cylindrical valve member is in this position, the water passes through slot 11 to chamber 9 and out through slot 12a into the enlarged portion of the sleeve 6 and is then conducted by the pipe 43 to the rim of the closet to refill the bowl. This downward movement of operating head 15 and valve member 7 continues until the washer 16 reaches its annular seat 17, after which no water will pass through the valve. The pressure continues to be built up in the chamber 4 until it equals the inlet pressure.

In order to assure filling of the bowl, the chamber 9 has a port 12a near the bottom thereof which normally opens into the enlarged lower end of the valve sleeve 6 and is so positioned that just as the valve opens and again just before the port 11 moves below the annular seat 17, will permit the flow of water through the chamber 9 into the jet discharge pipe 43. This, incidentally, allows water to completely drain out of the chamber 9 upon closing of the valve.

The by-pass from the passage 18 up through the dome into the chamber 4 must be a restricted passage in order that pressure will not build up too quickly in the chamber 4 and cause the valve to operate too rapidly. A small orifice would be likely to become clogged with small particles, and to prevent this I use the rod 26, which can be of any desired shape. I have here shown it as non-circular. When the valve moves up, the top of the rod 26 hits the plug 51 and is held stationary relative to the upwardly moving parts and against the pressure of the spring 29. The relative reciprocation between the stem 26 and the member 24 serves to dislodge any small particles which might enter this passageway. Of course when the valve begins to close, the spring 29 urges the member 26 back to its normal position, giving a reciprocating or wiping action in the reverse direction. Thus with every operation of the valve the member 26 wipes up and down in the passage 25, tending to break up and dislodge any foreign particles that might otherwise tend to clog this restricted passageway.

The Sanitary Code established by the Department of Commerce requires that a flushing valve connected directly with a water supply line shall be so constructed that in the event of the water supply being shut off in the basement so as to create a vacuum in the water supply line between the basement and the valve, there can be no suction of water from the closet bowl back into the water supply line. This is an extremely unlikely condition, but the check valve provided by the ball 20 guards against this. If there were a suction or vacuum on connection 3, this suction would be conducted to the annular passage 51 and on the under side of the operating head, thus pulling the operating head hard onto its seat 17, and holding the valve closed. But if there was no automatic check in the passage 19, this suction, or vacuum would be conducted to the top side of the operating head as well as the under side, and as the top side would have the greater area exposed to the suction, the suction would raise the operating head from its seat 17, and the suc-

tion would then draw the water from the closet through the pipes 43 and 45, through chambers 9, 10, the slots 12 and 13, the annular passage 51, the port 56 and through the connection 3 into the water supply line. The ball check prevents this by preventing the suction or vacuum passing through passage 19, thus holding the suction on the underside of the operating head only. If there were a suction on the connection 3 and the valve 34 were opened, thus establishing suction up through the pipe 45, the by-pass 41, 40, into the pressure chamber 4, the reverse pressure would cause the ball 20 to seat and thus prevent any fluid from traveling back into the water supply line by means of this route.

In the operation of the valve the plug 24 in the top of the dome 21 comes into contact with the vertically adjustable plug 51 in the top of the cap 5. By adjusting the plug 51 upwardly 20 the limit of upward movement of the valve is increased, and by adjusting the plug downwardly the limit of movement of the valve is decreased. By means of this the flushing period can be regulated within the necessary limits.

25 The closet bowl having the two passageways to the rim and the jet is conventional and the present invention contemplates no modification of the closet bowl. I have therefore shown only the portion of the closet bowl in which the valve 30 is mounted.

In Figure 5 I have shown the connection between the valve and the closet bowl. The closet bowl is designated 60 and it has at the back of it a vertically opening pocket 61. Leading off 35 from this pocket is a passage 62 that goes to the rim of the bowl, while the main portion of the pocket 61 communicates with the jet through the channel 63. As ordinarily constructed, the top of the pocket 61 has a slightly overhanging 40 flange 64.

According to my invention the lower end of the pipe 43 projects below the lower end of the outer pipe 45. At the lower end of the pipe 43 is an elbow 65 having a rubber gasket 66 therein 45 through which the lower end of the pipe 43 passes, there being a stop at 67 to limit the distance in which the pipe 43 may be entered in the elbow. The other end of the elbow carries a rubber plug or gasket 68 which fits into the passage- 50 way 62.

Surrounding the upper part of the elbow and the lower end of the pipe 43 is a connector 69 having a lower tapered portion 70, an intermediate threaded portion 71 and an upper threaded 55 portion 72, the three portions being of respectively smaller diameters.

On the intermediate threaded portion 71 is a flanged nut 73 for drawing the flared portion 70 upwardly into clamping engagement with the flanged portion 64 of the bowl, a rubber gasket 74 being interposed between the flared portion of the sleeve 69 and the nut. On the inside of the sleeve portion 70 are a plurality of laterally projecting lugs 75 for holding the upper end of 65 the elbow in concentric spaced relation to the inside of the member 69, water passages of course being formed between these lugs. The outer pipe 45 fits into the upper portion 72 of the member 69, there being a lug 76 to limit the extent to 70 which the end of the pipe 45 can project into the member 69. Screwed onto the outside of the portion 72 is a nut 77 for confining a packing 78 around the lower end of the pipe 45.

This connection can be made very quickly, and 75 where an alternating valve is provided, serves as

an effective means for distributing the water into the two channels. It will be understood that two channels are now commonly provided but alternating valves have never been used to flush water closets except in a few experimental cases. I 5 have shown an enclosing dome member at 79. This merely rests on the bowl and is confined to some extent by the nut 77.

In the arrangement shown in Figure 9 the construction throughout is substantially the same 10 as the construction shown in Figure 1, with the exception that the operating head, instead of having a cup leather 23 operating within a cylindrical pressure chamber 4, is carried on a flexible leather or similar diaphragm 80, this diaphragm 15 being clamped to the operating head in the same way that the cup leather is clamped. The valve casing, however, is made of a larger diameter and the periphery of the diaphragm is clamped between the seat 81 formed in the valve casing 20 itself, and a flange 82 extending down from the cap 5a. The diaphragm 80 of course permits of pressure responsive movement of the operating head in the same way as in the arrangement 25 previously described. Like reference numerals have otherwise been used in Figures 1 and 9 to designate the corresponding parts.

The arrangement shown in Figure 10 is provided where it is desired to have a pressure operated valve without the alternating feature. Without the alternating feature of course there is only one discharge pipe and all of the water discharges into this pipe so that the valve structure is much more simple and the plurality of ports as heretofore described is not necessary. In this figure, 30 the valve casing 90 is provided with an inlet connection 91. It has a cap 92 which is provided with the various features hereinbefore described. The control valve, similar to the valve 34, is not shown but is mounted on an extension 95 on the 40 housing. The pressure chamber is designated 96; 97 is the outlet port from the pressure chamber and 98 is the by-pass through which water bypassed from the pressure chamber is returned to the discharge pipe 99 attached to the lower end 45 of the valve casing. Within the valve casing is a cylindrical chamber or sleeve 100 in which the vertically reciprocating valve 101 has a sliding fit. The vertically reciprocating valve is provided with two annular inlet ports 102 and 103; 50 102 is the main port and 103 is an auxiliary port of smaller area than the port 102, and both ports have a combined area which is less than the area of the passageway 104 from the inlet connection portion 91 to the interior of the valve casing. The sliding valve 101 is carried on an operating head 105, the construction of which is similar to the operating head shown in Figure 1, or the diaphragm arrangement of Figure 9 may be used. The by-pass into the pressure chamber is the 55 same as that previously described. The operating head carries a washer 106 adapted to seat on the annular seat 107 at the top of the sleeve 100.

In operation, the cracking of the control valve allows fluid to escape from the pressure chamber 60 96, causing the operating head 105 to move up. The port 103 is first uncovered and then the port 102, and the flow of water through these ports goes into the discharge pipe 99. As the valve closes, the main port 102 is first shut off, leaving 65 a relatively restricted flow of water pass through the auxiliary port 103 for the purpose of filling up the closet bowl after the flushing has been completed. It is by reason of the fact that the area of the ports 102 and 103 is less than the area 70 75

of the passage 104 that the operation of the valve is secured. As previously pointed out, this is important in order that there will be a difference of pressure to operate the valve in both directions.

The advantages of my invention arise from the provision of a valve which is practical to construct, which will be operated both in opening and in closing by the pressure of the incoming water, and the valve does not require excessively large piping in order to supply it, as it is merely necessary that the water supply pipe shall have a carrying capacity equal to or greater than the capacity of the port 56 or 104, i. e., that is greater than the capacity of any discharge ports that are open at any one time, whereby a differential in pressure will always be maintained.

A further advantage resides in the adaptation of the invention to an alternating or distributing system. The arrangement is more simple to manufacture and is more satisfactory than the arrangement shown in my said Patent No. 1,660-352. Various other objects and advantages are obtained by the invention, as will be apparent to those skilled in the art. The mounting by which the valve is attached to the bowl is also highly advantageous.

While I have shown and described a preferred embodiment of my invention, it will be understood that various modifications and changes may be made in the construction shown within the contemplation of my invention and under the scope of the following claims.

I claim:

1. A valve of the class described comprising a casing having a water inlet connection and having two water outlet connections, a valve sleeve in said casing having a slide valve therein, a water passage in the casing around the upper part of the sleeve, upper and lower ports in the slide valve adapted to be moved successively into the water intake passage at the top of the sleeve upon movement of the slide valve upwardly, a channel in said sleeve communicating with one of said outlet passages, means for establishing communication between the upper port of the slide valve and the channel when the upper port first communicates with the water inlet passage and for closing communication between the upper port and the channel when the lower intake port of the slide valve communicates with the water inlet passage, said valve providing a passageway to the second outlet passage from the lower port, and a pressure responsive head for operating the slide valve.

2. A slide valve member for an alternating valve comprising a cylindrical body having a vertical partition dividing the interior of the body into two chambers, one of said chambers being closed at the bottom and having an inlet port therethrough in the side wall of the valve member adjacent the upper end thereof and having an outlet port therefrom positioned below the intake port and of greater area than the intake port, the bottom of the second chamber being open, and an intake port into the second chamber of less area than the outlet passage provided by the open end of the chamber, the intake port of the second chamber being located in a plane intermediate the intake and outlet ports of the first chamber.

3. A valve of the class described comprising a casing having one inlet and two outlets and hav-

ing a sleeve portion therein, said sleeve portion being of larger diameter at its lower end than at its upper end, a pressure responsive operating head in the valve casing above said sleeve portion, and a sleeve valve member carried by the operating head and received in said sleeve, said valve member being movable with the head from a lower normally closed position to an upper position, the lowermost end of said sleeve valve member opening into the enlarged lower portion 10 of said sleeve when the sleeve valve member is in its lower normally closed position, the sleeve valve member also having a port in the side wall thereof near its lower end which registers with said enlarged lower portion when the sleeve valve 15 member is in said lower position.

4. A distributing valve of the type having a valve casing with an inlet chamber and separate outlet ports, and a distributing sleeve valve member in the casing reciprocable therein for alternately directing water through said separate outlet ports and having a fluid pressure operated head connected with the distributing sleeve valve characterized by the distributing sleeve valve being provided with longitudinally separated inlet 25 ports and longitudinally separated outlet ports, the valve sleeve having partition means therein whereby the flow of water from one inlet port may be directed separately from water passing through the other inlet port, said outlet ports 30 in the valve casing being arranged for cooperation with the outlet ports of the distributing sleeve valve member.

5. A distributing valve of the type having a valve casing with an inlet chamber and separate outlet ports, and a distributing sleeve valve member in the casing reciprocable therein for alternately directing water through said separate outlet ports and having a fluid pressure operated head connected with the distributing sleeve valve 40 characterized by having one set of inlet and outlet ports and a connecting passage at one side of the center thereof, and another set of inlet and outlet ports and a connecting passage at the other side of the longitudinal center thereof, the 45 respective connecting passages being separated, the ports in the casing being arranged for cooperation with said ports in the sleeve valve member.

6. A valve of the class described, comprising a 50 valve casing having an inlet chamber and a sleeve portion, and having a reciprocable valve sleeve fitted in said sleeve portion, a fluid pressure operating head connected with said sleeve and arranged to move the valve sleeve back and forth 55 in the sleeve portion of the casing, said valve sleeve having a plurality of narrow slit-like peripheral ports therein adapted to be brought into register during the operation of the valve with the ports in the valve casing, said slit-like ports 60 in the valve sleeve having a width in the direction of movement of the valve many times less than the length of the ports whereby the complete covering or uncovering of said ports occurs in a relatively short travel of the valve sleeve, 65 two of said slit-like ports being near the upper end of the sleeve and constituting inlet ports and being on diametrically opposite sides of the sleeve, and partition means inside the sleeve for maintaining the flow of water which enters said 70 opposed inlet ports separate within the valve sleeve member.

THOMAS F. PAYNE.
